CONTAINER HOLDING MECHANISM

Filed Jan. 16, 1941

FIG. 1.

UNITED STATES PATENT OFFICE

2,315,196

CONTAINER HOLDING MECHANISM

Samuel J. Gallione, Columbus, Ohio

Application January 16, 1941, Serial No. 374,728

6 Claims. (Cl. 248—361)

This invention relates to apparatus for transporting containers and is particularly directed to a device for holding a filled container, such as a vase, basket or the like used by florists during transportation in a truck or other vehicle. Ordinarily, when floral pieces are being delivered by the florist, the vases or other containers in which they are positioned are placed in an ordinary flower pot of sufficient size and are then packed as securely as possible to prevent movement. This method of handling is highly unsatisfactory in that a large amount of time is required to so pack the pieces and then, due to the insecurity of the system and lack of dependability of the workmen performing the function, many pieces fall over or move around in the vehicle and are consequently damaged, sometimes necessitating the return thereof to the greenhouse to be reassembled. Another disadvantage is the expense involved, the period of use of the flower pots being very short due to breakage in handling.

The primary object of the present invention resides in the provision of a device for holding containers which will avoid the above objections to the holders now in use by, first, being easy to apply to the article to be held and thereby decreasing the time required to mount the article and, second, by securely holding the article and thus preventing damage during transportation.

Another object resides in the formation of a device of the character mentioned which may be employed to hold any container regardless of shape and size within predetermined limits.

A further object resides in providing a container holder having a base and elongated flexible cable members for securing the container to be transported to the base, pulley means for the cable members being adjustably supported by the base and held in various positions of adjustment with respect to the base through the operation of securing the container thereto.

A still further object is the formation of a container holder with a base and guide means extending across the same, the guide means receiving bracket members which in turn receive flexible cable means employed in securing containers to the base, the brackets being movable on the guide means to adapt the container holder to containers of various sizes and being provided with pulley means for reducing the wear on the cables as they are moved through the brackets in the operations of securing containers to and removing them from the holder.

Another object rests in providing a container holder having a base and a pair of cable guiding

pulleys adjustably mounted on the base, cable clamping means also being arranged on the latter to retain the cables in position of adjustment after a container has been secured to the base, the ends of the cable means being provided with hook members for engaging the article to be secured, said hook members being so secured to the cable as to admit of some yieldability whereby the cables may be maintained under a slight degree of tension after being adjusted into container holding relation.

Other objects will be apparent from the following description and the accompanying drawing in which a container holder constructed in accordance with the preferred form of the invention has been illustrated in detail.

In the drawing:

Fig. 1 is a perspective view of a container holding device formed in accordance with the present invention;

Fig. 2 is a detail vertical sectional view taken through one of the pulley carrying bracket members forming a part of the holding mechanism shown in Fig. 1;

Fig. 3 is a horizontal sectional view taken through a cable clamping member provided on the holding mechanism;

Fig. 4 is a detail sectional view taken on the plane indicated by the line IV—IV of Fig. 3;

Fig. 5 is a longitudinal sectional view taken through a container engaging element secured to one end of the cable means.

Referring more particularly to the drawing, the numeral 1 designates the base of the holding mechanism. In this instance, the base is rectangular when viewed in plan and is formed from sheet metal or other material capable of being cut and formed and yet possessing sufficient resistance to bending as to provide a rigid structure. The base 1 has a downwardly directed peripheral flange 2 which terminates at its edge in an inwardly directed lip 3. The lip and flange serve to reinforce the base and hold the body thereof in spaced relation from a support on which the base may be positioned. Other suitable means may be employed to reinforce the base to prevent its collapse under the weight of containers secured to the device.

The body of the base has a pair of guide slots 4 formed therein which extend from opposite corners toward the center of the base and terminate in spaced relation. Disposed in these slots for guided movement are a pair of bracket members 5, these being formed from plates 6 and angularly bent ears 7, the latter being welded or other-

wise secured to the upper surfaces of the plates in spaced relation. The ears are provided with aligned perforations for the reception of pivot members 8 upon which pulleys 9 are journaled. The ends of the pivots are headed to prevent the undesired release of the pulleys during the use of the device.

At one corner of the base, there is provided a housing 10 formed from a plate having a pair of downwardly directed corners 11 which engage the upper surface of the base and provide stop shoulders for spring members 12, the purpose of which will be hereinafter set forth. The plate 10 is spaced from the base by a stationary jaw block 13 having openings 14 at its ends for the reception of screws 15 employed to hold the plate and the block in connection with the base. Through the provision of the member 13 and the plate, a pair of cable guides are formed through which the ends of a cable 16 are trained. The ends of the cable are also trained through the bracket members and around the pulleys 9. The plate 10 and the upper wall of the base are provided with a plurality of registering openings through which pivots 17 extend, these being provided at their upper ends with shoulders to prevent the complete passage of the pivots through the openings. The lower ends of the pivots have holes for the reception of cotter pins 18 which prevent the removal of the pivots.

Two of the pivots 17 are disposed adjacent to the inner end of the stationary jaw 13 and receive pulley wheels 18. These members guide the cable ends and hold them adjacent to the sides of the jaw 13. Two other pivots are disposed in closer relation to the corner of the base and furnish pivotal axes for a pair of movable jaws 19 having arcuate cable engaging ends arranged adjacent to the stationary jaw and manually engageable extremities projecting therefrom on the opposite sides of the pivots from the cable engaging portions. The latter portions have spaced teeth formed on the arcuate surface to insure a better grip on the cables. The sides of the stationary jaw in registration with the inner ends of the movable jaws are arcuate and are also formed with spaced teeth to assist in preventing slippage of the cables.

Each of the movable jaws has a slot formed in one edge for the reception of the bent ends of the springs 12 which are composed of a plurality of relatively light gage leaves. This spring construction is preferable since the failure of one leaf will not leave the device entirely free but some pressure will remain to urge the movable jaw toward a rope engaging position. Through the provision of the jaws and springs, the former will be caused to pivot about the axes of the members 17 whereby the cable engaging ends will move toward the stationary jaw. When cables are positioned between the movable and stationary jaws, the springs will force the curved ends of the jaws into firm engagement with the cables and prevent their movement toward the center of the base. When it is desired to move cables in this direction, the extensions 20 may be engaged and manually moved toward one another to cause the jaws 19 to move away from the jaw 13, thus effecting the release of the cables.

As illustrated in Figs. 1 and 5, the ends of the cable adjacent to the pulleys 9 are provided with container engaging elements 21 which are hooked shaped to receive the upper edge of a container such as a vase indicated at 22. The elements 21 are so connected with the ends of the cable as to

permit a limited amount of longitudinal movement of the cable after the elements have been engaged with the container. To provide for this feature, the hook-shaped members 21 have elongated shanks 23 terminating at the ends in heads 24. These shanks extend through tubular members 25 in which compression springs 26 are disposed. One end of the spring in each member engages a shoulder at one end of the member 25 while the opposite end of the spring is engaged by the head 24, the spring being thus confined within the member 25. It will be seen that outward movement of the hooked end 21 will result in compressing the spring 26. To connect the member 25 to the cable, its end has a ferrule 27 clinched thereto, this ferrule being positioned in the member 25 and retained therein by turning the edge of the member 25 inward as indicated at 28. In this manner, the container engaging element may be flexibly connected with the cable and still be permitted to rotate with respect thereto.

After the device has been assembled, containers such as vases, urns and flower baskets may be secured to the base for transportation in a truck or other vehicle by positioning the container on the center of the base, placing the hook-shaped elements 21 over the upper edge of the container and exerting a pulling force on the looped portion 29 of the cable disposed outside of the housing 10. After the slack has been taken out of the cable between the jaws and the elements 21, a slight additional pulling force will place the springs 26 under tension and the container will then be positively secured to the holder. The tension in the springs will be transmitted to the cable and, since the major portions of the jaws 19 in engagement with the cable are disposed between the pivots 17 and the outer edge of the base, the tension in the cable will tend to draw the movable jaws into firmer engagement with the cable. After the container has reached its destination, it may be released from the holder by moving the extremities 20 toward one another and freeing the elements 21 from engagement with the container edge.

The holder is made adaptable to various size containers by making the brackets adjustable in the slots 4. This feature is accomplished by providing the plates 6 with openings for the reception of headed pins 30 which extend through the slots and are provided at their lower ends with a retaining cotter pin 31. Between the cotter pin and the under side of the base, there are positioned around the pin a pair of washers 32 and a spring 33. The spring urges the upper washer into engagement with the under side of the base and holds the brackets in movable engagement with the upper side. The brackets automatically assume their adjusted positions when a pulling force is imparted to the cable in securing a container to the holder.

While the elements forming the device may be composed of any desired material, the base, housing, pulleys, brackets and jaws are preferably formed of metal and the cable is preferably a woven rope such as sash cord. Other materials could be employed without departing from the spirit of the invention. While but a single embodiment of the invention has been illustrated, many minor changes may be made therein but it is believed that the form shown possesses the most advantages with the simplest structure.

What is claimed is:

1. A container holding device comprising a base having transversely extending guide slots

in the upper surface, bracket means mounted for longitudinal adjustment in said guide slots, a pulley carried by each bracket, cable clamping means mounted on said base, said means having a stationary jaw and a plurality of spring pressed clamping jaws mounted for pivotal movement toward and away from said stationary jaw, cable means extending between said stationary and flexible jaws and around said pulleys, and container engaging hook means carried by the ends of said cable means.

2. A container holding device comprising a base having transversely extending guide slots in the upper surface, bracket means mounted for longitudinal adjustment in said guide slots, a pulley carried by each bracket, cable clamping means mounted on said base, said means having a stationary jaw and a plurality of spring pressed clamping jaws mounted for pivotal movement toward and away from said stationary jaw, teeth means provided on said jaws, cable means extending between said stationary and flexible jaws and around said pulleys, container engaging hook means carried by the ends of said cable means, and spring means for yieldably connecting said hooks to said cable means.

3. A container holding device comprising a base, a pair of cable guides mounted on said base, a stationary jaw secured to said base, a pair of clamping jaws mounted for movement toward and away from said stationary jaw, flex-

ible cable means extending between said jaws and around said guides, and container engaging means carried by said cable means.

4. A container holding device comprising a base, cable guides mounted for adjustment toward and away from the center of said base, cable means extending around said guides, container engaging means fixed to said cable means, and means for clamping said cable means in container securing condition.

5. A container holding device comprising a base, cable guides mounted on said base, cable means extending around said guides, container engaging elements fixed to said cable means, and means for clamping said cable means in positions of adjustment.

6. A container holding device comprising a base, guide means extending radially with respect to a predetermined point on said base, direction changing means for cables adjustably positioned in said guide means, cable means extending around said direction changing means, container engaging hooks, means yieldably connecting said hooks to said cable means, said connecting means being placed under tension when a pulling force is applied to said cable while said hooks are engaged with a container, and cable gripping means carried by said base to maintain said hook and cable connecting means under tension.
